UNITED STATES PATENT OFFICE

FRANCOIS ROCHEFORT, OF PARIS, FRANCE

METHOD OF INJECTION OF FUEL FOR INTERNAL COMBUSTION ENGINES

Application filed May 27, 1927, Serial No. 194,768, and in France June 3, 1926.

The present invention relates to the direct supply of fuel to internal combustion engines in general, and more particularly to engines in which the opening of the atomizer 5 or injection valve is effected by the fuel itself, forced under pressure by the feed pump or distributor.

Numerous arrangements are already known for injecting fuel by utilizing compressed air alone as the mechanical agent for atomizing and diffusing the liquid fuel. Arrangements are also known in which the fuel is broken up or atomized by compressed air or gas within the injector and during the 15 period of injection and diffusion in the interior of the engine cylinder.

In order to retain the advantages resulting from injection by means of compressed air or compressed gas, whilst avoiding the 20 use of an auxiliary compressor, which in the case of light, high-speed and low-power engines, may constitute a complication and a source of trouble by reason of the delicacy of working of this kind of apparatus, it has 25 been proposed to provide a small chamber for storing up hot air and gases drawn off from the working cylinder during the preceding compression and combustion strokes or phases; these gases afterwards serve for 30 atomizing and diffusing the fuel at the moment of injection, by projection of the fuel into the working cylinder at the moment of the opening of the injection valve.

But these arrangements involve numerous 35 inconveniences:—

1. The air and the gas are drawn or tapped off from the working cylinder by means of a poppet valve or an automatic non-return valve, which cannot ensure accuracy as regards its opening and closing.

2. The drawing off of the burning gases from the cylinder involves a lessening of the useful driving force, which is in general a greater drawback to efficiency than would 45 be the use of an auxiliary compressor, considering the enormous fall of temperature suffered by these gases during the time of their storage in the chamber.

3. These gases, being already burnt, have 50 thus become inert and their introduction into

the working cylinder during the injection prevents a homogeneous mixture being obtained and affects the rapidity of combustion.

4. It is impossible to avoid the carry-over 55 of residues of combustion into the chamber by these burnt gases; the result is that in the latter there are formed carbon deposits which prevent the valves or injection needles being kept tight, and in general rapidly foul 60 the pipes through which the fluid or the two fluids have to flow.

It is easy to understand that in spite of the simplicity of these various solutions, it has not been possible to obtain security of working by such means. In general, the injection of the liquid fuel into the cylinder takes place in a form too massive to permit the employment of high working speeds of the engines, and vaporized liquid fuel is found 70 in the exhaust gases; this fuel has therefore been evacuated without having been able to burn inside the cylinder during the insufficient time of the combustion period.

The present invention has for object to 75 remedy these drawbacks and to improve considerably the results obtained by compressed-air or compressed-gas injection, in order to permit also the reasoned use of high tension electrical ignition, exactly as for a mixture of air and petroleum spirit, but while utilizing heavy oils, mineral or vegetable, as fuel; this electrical ignition constitutes in effect an essential condition for obtaining high speeds of rotation and wide limits of working, 80 which ensure the flexibility in working of the petroleum spirit engine.

In conformity with the invention, there is provided a chamber communicating with the working cylinder by nozzles or twyrs controlled by a valve, serving at the same time for the injection of the liquid fuel, and operated by the liquid fuel delivered under pressure in such a way that the latter, already squeezed or reduced to a film and atomized at the time of its admission by the injection valve, is sent, towards the end of the period of compression in the cylinder, by a part of the carburetted mixture compressed in the cylinder and flowing through 95 100

these nozzles or twyers, and is carried along into the chamber, passing through the injection valve, which latter is closed from just before the point of ignition until the commencement of the following compression stroke, when the mixture, vaporized in the chamber, returns by the twyers into the working cylinder, by reason of the difference of pressure between the chamber and the working cylinder, before being compressed and ignited, whilst a part of the fresh carburetted mixture is directed into the chamber at the end of this compression period.

The principal agent for diffusing the fuel in the working cylinder is thus formed by a part of the carburetted mixture, drawn off from the working cylinder at the end of the compression stroke and introduced into a capacity, of determinate volume and shape, which capacity is preferably located immediately above the injection valve which places it in communication with the working cylinder. The charge of fuel, delivered by the distributor or the pump which regulates its quantity as well as the duration of its distribution, serves to open the injection valve and to keep it open during the charging and the discharging of this capacity; the liquid fuel, distributed gradually during the charging period, is reduced to a film and atomized mechanically by the valve, whilst the hot carburetted mixture coming from the working cylinder ensures the diffusion of this fuel in the mixture chamber or capacity. The delivery of fuel by the distributor ceases just before the mechanically operated closing of the injection valve. The fuel is subjected to a vaporization as complete as possible in the capacity serving as mixture chamber, which is maintained in any suitable manner at a temperature favourable to this vaporization, but lower than the ignition temperature of the gaseous mixture compressed in this chamber. On the other hand the communication between the chamber and the engine cylinder being suppressed by the positive closing of the injection valve just before ignition in the cylinder, no burning gas can penetrate into this chamber; vaporization takes place rapidly during the whole time that this chamber remains closed.

The invention is applicable both to four-stroke engines and to two-stroke engines; the annexed drawing represents by way of example, in axial vertical section, the arrangement according to the invention in its application to a two-stroke engine.

Above the working cylinder *a* there is provided a chamber *b* communicating with the interior of the cylinder by means of nozzles or twyers *c* arranged in suitable number and in a circle around the axis of the fuel-injection valve. This valve is composed of a flat body *d*, which is designed to

bear upon a flat seating *b*¹ formed in the wall of the chamber *b* and which is integral with a cylindrical portion *d*¹, in the shape of a piston, located in a cylindrical bore *b*² formed in the thickness of the wall of the chamber *b*. The external diameter of this piston is slightly less than the internal diameter of the bore, so as to ensure an annular and exactly calibrated clearance between the external cylindrical surface of the piston and its cylindrical housing *b*².

The liquid fuel is delivered under pressure by the distributor (not shown), which is connected with a passage *b*³, formed in the thickness of the wall of the chamber *b* and extending below the piston *d*¹ to the bottom of the cylindrical bore *b*² serving as housing for the latter. Under the pressure of this fuel, delivered at the correct moment and for a suitable duration by the injection pump, the piston *d*¹ is lifted, carrying with it the valve *d* which is slightly separated from the seat *b*¹; the liquid fuel passes through the very small but exactly calibrated annular clearance formed between the cylindrical piston *d*¹ and its housing *b*² and arrives in the form of a thin film between the valve *d* and its flat seating *b*¹.

The height of lift of the valve *d* is limited by an abutment rod *e*, arranged and guided vertically in the upper part of the chamber *b*, in a plug *f* screwed into the latter; this rod *e* carries a ball *e*¹ which comes into engagement with one of the extremities of a rocking lever *g*, pivoted at *g*¹ and connected at *g*² to the operating mechanism (not shown) for closing the valve *d*. The rod *e* is subjected to the action of a coiled spring *e*² which surrounds it and tends constantly to maintain the lower extremity of the rod *e* separated from the ribs at the upper part of the valve *d*; the fuel, delivered under pressure by the distributor, need not therefore, in order to lift the valve *d* from its seat *b*¹, ever lift the rod *e*, but has solely to overcome the inertia of the valve *d* *d*¹, which is very slight by reason of the fact that the piston *d*¹ and the valve *d* are hollow. A cap *e*³, screwed upon the central part of the plug *f*, around the ball abutment *e*¹, limits the lift of the rod *e* under the action of its recall spring *e*². In the mechanism effecting the closing of the valve, there is interposed a spring or other elastic device (not shown), in such a way as to prevent damage to the parts when the rod *e*, under the action of the rocking lever *g*, brings the valve *d* back upon its seat *b*¹, thereby cutting off the admission of liquid fuel.

For the explanation of the working of this arrangement, it will first be supposed that the engine is running normally and that the chamber *b* is filled with a carburetted mixture which has been supplied thereinto at the end of a preceding compres-

sion stroke, as will be hereafter explained.

At the beginning of the period of compression in the working cylinder *a*,—after the closing of the one or more scavenging-air admission orifices *a*¹, which takes place with a certain delay relative to the closing of the one or more exhaust ports *a*², that is to say when the piston in its upward movement reaches the position 1—1 in the cylinder, in such a way as to ensure a full charge and even a supercharge in the cylinder,—the fuel distributor commences to deliver the fuel, which determines the opening of the injection valve *d*. The admission of fuel, between the flat valve *d* and its seating *b*¹, takes place at first with a very small output, which proceeds to increase gradually. At this moment, the rich carburetted mixture, which is in the chamber *b* at a pressure very near the final pressure of compression, expands violently into the working cylinder *a*, passing beneath the valve *d* and through the nozzles *c*; these latter are formed and arranged in such a manner as to obtain the maximum transfer-speed of the fluid for a fixed relation of the pressures respectively existing in the working cylinder *a* and in the chamber *b* during the injection stage. This injection into the working cylinder takes place at the moment when the whole air is still in motion in the latter; intimate mixture between this air and the carburetted mixture, coming from the chamber *b*, is the more facilitated as it is a question of two gases having densities differing very little from one another.

The piston continuing its compression stroke in the working cylinder *a*, there is first produced an equilibrium or balance of pressure between the latter and the chamber *b*; this equilibrium is afterwards upset, the pressure becoming higher in the working cylinder. The delivery-speed of the fuel-pump is then accelerated; the valve *d*, of which the lift is then limited by its stop *e*, is unable to rise further from its seating; the liquid fuel admitted by this valve is then squeezed or reduced to a film and atomized mechanically by the calibrated clearance formed between the small valve-guiding piston *d*¹ and its housing *b*².

The speed of the working piston increasing (for example when the piston has arrived at the position 2—2 in its upward stroke), by reason of the excess pressure in the cylinder *a*, the carburetted air passes at high speed through the nozzles or twyers *c*, in a direction opposite to the flow of the carburetted mixture at the beginning of the compression stroke; this carburetted air carries along the greater part of the liquid fuel charge admitted by the valve *d*, diffusing this fuel in the chamber *b* wherein the mixture is vaporized; for this purpose, the chamber is protected against external radi-

ation by a casing *h* and is heated by an electrical resistance *i* arranged within the chamber *b*; this resistance takes the form of concentric rings separated by insulators and connected electrically on the one hand to the wall of the chamber *b*, forming an earth return, and on the other hand to an electrical conductor *i*¹ connected to any suitable source of current. This resistance, at the time of starting and at moments when it is necessary, is raised by the passage of a current to a temperature which ensures the maintenance within the chamber *b* of a temperature favourable to the vaporization of the carburetted mixture contained in the latter, but lower than the point of ignition of the rich mixture compressed therein.

This chamber *b* might also be heated by a supply of exterior heat or, previously to using heavy oil, by running the engine on motor spirit for some short time.

Communication between the working cylinder *a* and the mixing and vaporizing chamber *b* is interrupted by a positive closing of the injection valve *d*, as above described, for example, when the piston reaches the position 3—3, some instants before the ignition point which takes place when the piston is at 4—4 in the cylinder. No gas under combustion can therefore pass from the cylinder *a* into the chamber *b*. The ignition of the charge is preferably carried out by means of one or more high tension sparking plugs arranged at *a*³.

Vaporization continues in the chamber *b* during the whole of the time during which this chamber remains closed, that is to say during the period of combustion, expansion and exhaust, until the start of the following compression stroke, when the opening of the injection valve *d* allows the suitably vaporized carburetted mixture to return from the chamber *b* into the cylinder.

The chamber *b* should preferably be of a shape ensuring a complete evacuation of the still liquid fuel during the injection into the working cylinder, at the beginning of the period of compression.

It is to be noted that the charge from the chamber *b* is in no way derived or drawn off from the normal cylinder-charge, because this chamber *b* discharges itself into the working cylinder when the latter has been completely filled, and when all the distribution orifices are closed at the start of the compression stroke, and an equivalent charge passes back from the cylinder into the mixing chamber at the end of the period of compression. There is thus a simple exchange of gaseous masses of different qualities without variation of quantity.

It may be remarked that the ignition is greatly facilitated by the fact that each time there is withdrawn from the cylinder a charge of carburetted air, which is injected

anew into the working cylinder after vaporization in the mixing chamber before being ignited.

At the time of starting the engine, since the chamber *b* does not enclose a charge of carburetted air, there occur several up and down strokes of the piston in the cylinder before ignition takes place; the air compressed by the piston carries along and diffuses in the chamber liquid fuel squeezed out and atomized mechanically by the valve *d*; the carburetted mixture is admitted into the cylinder at the beginning of the next compression stroke, merely to be forced back into the chamber *b* with a new charge of air and fuel at the end of the period of compression; these operations are repeated until the mixture is sufficiently carburetted and sufficiently vaporized to permit its ignition.

There may be mixed, with the charge of carburetted air in the vaporization chamber, a gas which would be diffused at the same time as the mixture, in order to activate the combustion of heavy fuel oils; this gas might also be a combustible gas.

In the case of an engine with several cylinders, all the mixing and vaporizing chambers of the different cylinders may be connected together by pipes of very small sectional area, so as to equalize the pressures and the speeds of injection between all the cylinders.

It is to be understood that without in any way departing from the principle of the present invention, numerous modifications in detail may be made in the form of construction which has been illustrated and described by way of example. Thus, one might employ another type of valve for the injection of the fuel, for instance those described in my prior patent specifications No. 197,934 and No. 228,468.

What I claim is:

1. The method of operating an internal combustion engine which comprises, providing two normally segregated bodies of gaseous nature, one body being located within the compression chamber of the engine, subject to compressive variations incident to the change of capacity of said compression chamber, and the other body being definitely bounded outside the compression chamber, placing said bodies into restricted communication during the compression stroke of the engine, thereby producing a tidal flow from the outside body to the one within the compression chamber on the early phase of the compression stroke, and in contra-direction on the later phase of the compression stroke, admitting liquid fuel under pressure in the form of a film to said bodies at said point of restricted communication during the period of their tidal flow, and controlling the duration of said restricted communication, thoroughly pulverizing said liquid fuel

by means of the tidal flow from the outside body to the one within the compression chamber on the early phase of the compression stroke, and in contradistinction on the later phase of the compression stroke trapping the outside body of gaseous matter thus enriched with liquid fuel by positively cutting off said restricted communication just previous to the ignition point in said compression chamber and maintaining it cut off until the beginning of the next compression stroke, and thoroughly vaporizing said trapped body of gaseous matter.

2. The method of operating an internal combustion engine which comprises, providing two normally segregated bodies of gaseous matter, one body being located within the compression chamber of the engine, subject to compressive variations incident to the change of capacity of said compression chamber, and the other body being definitely bounded outside the compression chamber, placing said bodies into restricted communication during the compression stroke of the engine, thereby producing a tidal flow from the outside body to the one within the compression chamber on the early phase of the compression stroke, and in contra-direction on the later phase of the compression stroke, admitting liquid fuel under pressure in the form of a film to said bodies at said point of restricted communication during the period of their tidal flow, and controlling the duration of said restricted communication, thoroughly pulverizing said liquid fuel by means of the tidal flow from the outside body to the one within the compression chamber on the early phase of the compression stroke, and in contradistinction on the later phase of the compression stroke trapping the outside body of gaseous matter thus enriched with liquid fuel by positively cutting off said restricted communication just previous to the ignition point in said compression chamber and maintaining it cut off until the beginning of the next compression stroke, and maintaining said trapped outside body of gaseous matter at a temperature favorable to its vaporization, but lower than the ignition temperature of the charge in the compression chamber of the engine.

In testimony whereof I have signed my name to this specification.

FRANÇOIS ROCHEFORT.
